UNITED STATES PATENT OFFICE.

FREDERICK HYDER, OF PITTSFIELD, MASSACHUSETTS.

ELECTRIC IMPRINTER.

1,119,701.

Specification of Letters Patent. Patented Dec. 1, 1914.

Application filed January 31, 1914. Serial No. 815,810.

To all whom it may concern:

Be it known that I, FREDERICK HYDER, a citizen of England, residing at Pittsfield, in the county of Berkshire and State of Massachusetts, have invented new and useful Improvements in Electric Imprinters, of which the following is a specification.

This invention relates to electric imprinters especially adapted to be used for applying imprints or embossed characters to paper, envelopes and the like and it consists in the novel features hereinafter described and claimed.

An object of the invention is to provide an imprinter of the character indicated which is of simple structural arrangement and which may be used in combination with a press or other machine or may be used independently for the purpose of applying the imprint or embossing to the material as indicated.

With the above object in view the imprinter comprises a casing mounted upon a base and a magnet located in the casing. A core is movably mounted in the magnet and means is provided for limiting the movement of the said core. A plunger is slidably mounted adjacent the side of the casing and carries at its lower end a die which is adapted to cooperate with a die mounted upon a portion of the casing. A lever is fulcrumed upon the casing and one end of the said lever projects into the path of movement of the core. An eye bolt is pivoted at one end to the plunger and the other of the said bolt is adjustably connected with the said lever. A spring is provided for returning the parts to normal position after they have been operated to accomplish the imprinting or embossing.

In the accompanying drawing:—Figure 1 is a side elevation of one form of the imprinter with parts broken away and parts in section. Fig. 2 is a top plan view of the same. Fig. 3 is a side elevation of a modified form of the imprinter with parts broken away and parts in section.

The imprinter comprises a casing 1 which is mounted upon a base 2 the said base being adapted to be applied to any suitable foundation in any appropriate manner. A magnet 3 is housed within the casing 1 and the said casing is provided at its side with openings 4 through which wires may be passed and connected with the magnet 3 in any desired manner. The said wires are

not shown but they are used for the purpose of transmitting electric current to the magnet 3 in order to energize the same. Any suitable timing device (not shown) 60 may be employed for sending the current over or along the said wires to the magnet 3 at desired intervals. A stud 5 is movably mounted in the base 2. A nut 6 is screw threaded upon the said stud and bears 65 against the upper surface of the base. Consequently it will be seen that by turning the nut 6 the said stud may be moved longitudinally in the said base. A core 7 is 70 slidably mounted in the magnet 3 and casing 1 and the said stud 5 is located in the path of movement of the said core and in longitudinal alinement with the same. In the form of the invention as illustrated in Figs. 1 and 2 of the drawing the upper end 75 of the core 7 projects slightly above the top of the casing 1. Ears 8 are provided at the top of the casing 1 and a lever 9 is fulcrumed between the said ears. One end of the lever 9 extends over the upper end of 80 the core 7 and is in contact with the same. Guides 10 are located at the side of the casing 1 and slidably receive a plunger 11 which in turn carries at its lower end a detachable die 12. An eye bolt 13 is pivotally 85 connected with the upper end portion of the plunger 11 and the said bolt passes transversely through one end portion of the lever 9. Nuts 14 are screw threaded upon the upper portion of the eye bolt 13 and bear 90 against the opposite sides of the lever 9 and serve as means whereby the said eye bolt 13 may be adjusted with relation to the lever 9 and when at a desired point of adjustment with relation to the lever may be secured by tightening the said nuts 14 against the opposite sides of the lever. A spring 95 15 is interposed between the lowermost nut 14 and the top of the guides 10 and is under tension with a tendency to force the 100 nuts 14 away from the upper end of the guides 10. The casing 1 is provided at its lower portion with an outstanding shelf 16 which is adapted to support a detachable die 17 the said die 17 being located immediately below the die 12.

In operation the imprinter works as follows. The strip of paper or other article to receive the imprint or impression is passed in the space between the dies 12 and 17 and 110 then the magnet 3 is energized by the application of an electric current thereto as herein-

before described whereby the core 7 is moved longitudinally in a vertical direction away from the stud 5. The upward movement of the core 7 swings the lever 9 whereby the 5 end of the said lever which is above the guides 10 is caused to descend against the tension of the spring 13. The downward movement of the outer end of the lever 9 moves the bolt 13 correspondingly and in 10 turn the plunger 11 is caused to descend whereby the guide 12 is carried down against the upper surface of the material between the said dies 12 and 17 and consequently the imprint or embossing is applied to the said 15 material. As soon as the magnet 3 is de-energized the core 7 drops by gravity against the upper end of the stud 5 and the spring 15 elevates the bolt 13 and the parts attached thereto whereby the inner end of the said 20 lever 9 is caused to descend with the core 7. By adjusting the stud 5 the space between the dies 12 and 17 may be regulated when the said dies are at their farthest positions from each other. Therefore adjustments 25 may be made for applying the imprint or embossing to relatively thin or thick material.

In the form of the invention as illustrated in Fig. 3 the upper end of the core 7 does not extend through the top of the casing 1 but the lever 9 is connected with the lower end of the said core by means of a yoke 18 so that the longitudinal movement of the said core is transmitted to the lever 35 9 by the said yoke. An advantage gained by this construction is that the top of the casing 1 is closed and consequently dust or other foreign articles cannot settle or enter the casing 1 through the top thereof.

10 In both forms of the invention the lower portion of the core 7 projects for a greater distance beyond the lower end of the magnet than the upper portion of the said core, consequently when the magnet is excited the 45 core 7 will be moved in an upward direction. An object of providing the adjustable stud

5 or the nut 6 as shown in Fig. 3 for limiting the movement of the core 7 in the direction away from the lever is that in the event that the core 7 does not move promptly the said 50 adjustable means may be manipulated so that the difference in the length of the end portions of the core 7 beyond the ends of the magnet may be regulated. When the core 7 is adjusted as above indicated the nuts 55 14 may be manipulated whereby the dies 12 and 17 may be maintained at a relative distance apart.

Having described the invention what is claimed is:—

1. An imprinter comprising a casing, a lever fulcrumed upon the casing, a plunger guided along the casing, means operatively connecting the plunger to the lever, a shelf carried by the casing, said shelf and said 65 plunger adapted to carry dies, a magnet located in the casing, a core located in the magnet and movable toward and away from the lever, the lever adapted to be swung by the movement of the core toward the same, 70 and adjustable means for limiting the movement of the core in the direction away from the lever.

2. An imprinter comprising a casing, a core movably mounted therein, means located in the casing for moving the core when excited, a stud adjustably mounted at the base of the casing and located in the path of movement of the core, a lever fulcrumed upon the casing and adapted to be swung 75 by the movement of the core, a plunger slidably mounted along the casing and adapted to carry a die, means operatively connecting the plunger with the lever, said casing having a shelf adapted to carry a die, said shelf 80 being located below the plunger.

In testimony whereof I affix my signature in presence of two witnesses.

FREDERICK HYDER.
